(57) **CLAIM**

The ornamental design for an induction range, as shown and described.

DESCRIPTION

FIG. 1 is a perspective view of an induction range, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is an enlarged view of Section 8, as shown in FIG. 6. The broken lines in the figures are for environmental purposes only and form no part of the claimed design.

The dash dot line shown in FIG. 6 forms no part of the claimed design, but is instead intended to identify the area of the enlarged view shown FIG. 8.
